W. J. LAUER

DENTAL SYRINGE NOZZLE

Filed Jan. 17, 1925

Inventor

W. J. Lauer.

By Attorney

UNITED STATES PATENT OFFICE.

WILLIAM J. LAUER, OF ARGYLE, MINNESOTA.

DENTAL SYRINGE NOZZLE.

Application filed January 17, 1925. Serial No. 3,154.

The present invention relates to a dental appliance for delivering warm air to the cavity of a tooth for evaporating moisture and one of the objects of the invention is to prevent the overheating of the nozzle and the burning of the lips when the nozzle is introduced into the mouth before delivering a blast of warm air into the cavity of the tooth under treatment.

10 Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

20 Referring to the accompanying drawings forming a part of the specification,

Figure 1 is a side view of a dental syringe nozzle embodying the invention, the dotted lines showing a portion of the usual bulb, and

25 Figure 2 is a central longitudinal sectional view of the nozzle.

Corresponding and like parts are referred to in the following description and designated in both views of the drawings by like reference characters.

The nozzle of a dental syringe constructed in accordance with the present invention comprises a metal tube 1 which is curved laterally at one end as indicated at 2 and to the opposite end of which is fitted a coupling 3 of usual formation for attachment of the nozzle to a soft rubber bulb 4. A tip 5 of approximately ball shape is fitted to the 35 curved end of the tube 1. A protector or

sheath 6 of refractory material such as fibre is fitted upon the tube 1 and is spaced therefrom as indicated at 7 and this protector or sheath extends substantially the entire length of the tube 1 and is contracted at opposite 45 ends to obtain a close fit and result in the provision of an enclosed space 7 which operates as a non-conductor to prevent the heating of the sheath or protector 6. For symmetry of appearance the sheath or protector 50 6 tapers throughout its length, the smaller end being adjacent the tip of the nozzle and the larger end adjacent the coupling 3 and receiving the inner end thereof.

What is claimed is:—

1. A dental syringe nozzle comprising a tube having a laterally offset tip end, a sheath surrounding the tube adapted to abut said end, the bore of said sheath being enlarged with respect to the tube to provide 55 a non-conducting space, and a detachable coupling engaging said tube centering and securing the sheath in place, said coupling being adapted for connection to a bulb.

2. A dental syringe nozzle comprising a 60 tube having an offset tip end, a sheath surrounding said tube having one end in intimate engagement with the tube and in contact with the offset end, said sheath having its bore enlarged with respect to the tube to 65 provide a non-conducting space, a coupling for connection to a bulb or the like, said coupling being detachably threaded on one end of the tube, and said coupling extending partly into the sheath to center it and having 70 a portion abutting the adjacent end thereof to secure the same in place.

In testimony whereof I affix my signature.

WILLIAM J. LAUER.
